UNITED STATES PATENT OFFICE.

ROBERT N. PERCY, OF BATTLE CREEK, MICHIGAN.

VALVE-GEAR FOR ENGINES.

SPECIFICATION forming part of Letters Patent No. 409,061, dated August 13, 1889.

Application filed February 7, 1889. Serial No. 299,068. (No model.)

To all whom it may concern:

Be it known that I, ROBERT N. PERCY, a citizen of the United States, residing at Battle Creek, in the county of Calhoun and State of Michigan, have invented certain new and useful Improvements in Valve-Gear for Engines, of which the following is a specification, reference being had to the accompanying drawings, making a part of this application.

10 The object of this improvement is to provide a durable, easily-constructed, and reliable substitute for the "link-motion," so called; and it consists in certain peculiarities in the construction, arrangement, and combination of parts, substantially as hereinafter set forth, and particularly set forth in the subjoined claims.

My improvement relates to a novel arrangement of the actuating-lever and reversing-gear carrying a shifting eccentric, in connection with double-incline planes placed in reverse position on the engine-shaft, means for holding and guiding said eccentric and for adjustably fixing the incline planes relatively 25 to the eccentric-slot and operative parts, whereby the lost motion caused by wear is readily corrected, and also new methods for reducing the friction of the reversing-device surfaces to a minimum, and tendency to torsion is overcome. Other obvious advantages 30 incidentally accrue, which will fully appear presently.

In the drawings, wherein like letters and figures of reference designate corresponding parts in all the views, Figure I is a side view of the shifting eccentric, showing the position thereof at half-stroke and the main engine-shaft in cross-section. Fig. II is a central horizontal section of my invention, giving a 35 longitudinal view of that portion of the engine-shaft on which it operates, showing the incline planes in proper position when the eccentric-rod is at the extremity of its backward stroke. Fig. III is a horizontal section 40 of the eccentric, showing a portion of the shaft, the eccentric-disk D'', and the sliding collar or sleeve D'. Fig. IV is that form of the eccentric having its shaft and incline-plane slots in its center, with its rod *i* reaching at 45 right angles therewith, and showing the shaft in center of said eccentric in cross-section.

Fig. V is a horizontal section of the eccentric embracing disks and guides D D'', showing the manner of removably attaching them to the engine-shaft by means of the set-screws *t t*. 55 Fig. VI is a side view of the eccentric with the engine-shaft in cross-section, exactly similar in form to that shown in Fig. IV, save that here the slot for the eccentric and incline planes is placed upon one side of the center 60 thereof for the purpose of securing greater precision of the valve-motion throughout its stroke, according to the length of rod and angle of advance of the varying styles of engines now in use. Fig. VII is an enlarged 65 section of that portion of the eccentric shown on line *xx*, Fig. IV, where the wedge or incline-plane slot is represented at *m m*, and where a shoe *k* engages between said incline plane and the adjacent shoulder of the eccentric. 70 (See Fig. VII.) This shoe is to facilitate the fitting to and reduce the friction of the contacting parts at this point.

A A' are the incline planes or wedge-shaped blocks, of suitable length and thickness, 75 placed central and longitudinally equidistant above and below the shaft. These incline planes are nicely fitted to, and, with the shaft and eccentric-disk bearings, slidingly fill and fit the vertical slots of the eccentric. The 80 larger end of the incline plane A is firmly fixed to the shifting and sliding sleeve D'' by means of the bolt *c*', while its opposite and smaller end is provided with the bolt and adjustable nuts *c*'', by means of which lost motion caused by wear is corrected. The two 85 incline planes A and A', being thus placed and adjusted in relatively opposite positions on the main shaft, at all times fit and fill the eccentric-slots at any and every point of 90 their sliding movement on the shaft, as clearly seen by dotted lines, Figs. I and II.

B is the main engine-shaft, and D D''' are eccentric embracing-disks, provided with suitable sleeves for the purpose of removably fixing them to the shaft by means of set-screws *t t*. (See Fig. V.) These disks are slotted suitably to receive the incline planes A A', in form corresponding to the slots of the eccentric *m m*, as clearly shown in Figs. I, II, IV, 95 and VI.

Sliding sleeves or disks D' D'' loosely play

on the shaft B, and to these are firmly fixed the incline planes A A', vertically of and equidistant from the shaft center, as already seen, thus forming a revolving frame carrying 5 the sliding incline planes and its sliding connections along on the said shaft longitudinally, while the vertically-shifting eccentric Y remains stationary on, yet revolving with, the shaft, but governed in its vertical movement 10 and consequent oscillations of its rod *i* by means of the sliding devices described, actuated through the well-known hand-lever *h* and its bell-crank and engaging disk or sleeve D".

15 The shifting eccentric Y is provided with a central or nearly central slot for passing the sleeve of the fixed disk D" in the usual manner, and to receive my improved inclined planes A A' and shaft B, and when that device 20 is employed the tops of the eccentric-slots *m* should be pivoted to the shoe *k*, as shown, Fig. VII.

The fixed eccentric embracing-disk D''' is provided with a V-shaped vertical channel *d*, 25 which engages with and forms a "way" or track and guide for a V-shaped corresponding projection, with which the shifting eccentric is provided, said projection and way running parallel and vertical with the eccentric-slots 30 *m*, the office of which is to reduce the friction encountered in shifting the eccentric from the tendency to torsion at this point.

Where sufficient space on the main engine-shaft cannot readily be found for attaching 35 my improvement, a sub-shaft having revolution in equal time may be employed at slight cost, and thus my improved substitute for the costly and complex "link" heretofore mostly in common use may be adopted with useful 40 results.

Having thus fully illustrated and described

my invention, what I claim, and desire to secure by Letters Patent of the United States, is—

1. In an engine valve-gear, a shaft, and incline planes placed above and below said shaft, in combination with a vertically-shifting eccentric formed with a slot adapted to receive said incline planes, and a shoe having its bearing on the top of said incline planes. 45

2. In an engine valve-gear, a shaft and incline planes placed centrally above and below said shaft, in combination with a vertically-shifting eccentric provided with a shoe having its bearing on the top of the said incline planes. 55

3. In an engine valve-gear, a shaft, incline planes placed above and below said shaft, and a shoe having its bearing on said incline planes, in combination with a shifting eccentric pivoted to said shoe, substantially as shown, and for the purpose set forth. 60

4. In an engine valve-gear, the shaft provided with a revolving frame, which frame consists of sliding sleeves and incline planes, 65 in combination with a shifting eccentric and a shoe having its bearing on said incline planes.

5. In an engine valve-gear, a shaft, incline planes placed above and below said shaft, 70 and a slotted embracing-disk for said incline planes, in combination with a shifting eccentric and a shoe having its bearing on said incline planes.

In testimony that I claim the foregoing I 75 hereunto affix my signature in the presence of two attesting witnesses.

ROBERT N. PERCY.
